SUPPORT LEG FOR A WHEEL ALIGNER

John Roy Bateman, 5217 Hollywood Blvd.,
Hollywood, Calif. 90027

Filed Mar. 5, 1969, Ser. No. 16,055

Term of patent 14 years

Int. Cl. D15—99

U.S. Cl. D55—1

FIG. 1 is a front view of a support leg for a wheel aligner showing my new design.

FIG. 2 is an edge view thereof as seen from the right side of FIG. 1.

FIG. 3 is a vertical sectional view as taken on the line 3—3 of FIG. 1.

FIG. 4 is a fragmentary cross-sectional view as taken on the line 4—4 of FIG. 2.

I claim:

The ornamental design for a support leg for a wheel aligner, substantially as shown.
